CONTACT BANK

Anthony Winther, Kenosha, Wis., assignor to
 Martin P. Winther, Waukegan, Ill., as trustee

Application March 7, 1934, Serial No. 714,436

4 Claims. (CL. 200—1)

This invention relates to contact banks, and with regard to certain more specific features, to contact banks for successively cutting in and cutting out sections of a resistance bank.

5 This invention is an improvement upon the structure disclosed in my United States Patent 1,982,461 for Electric governor, dated November 27, 1934.

10 Among the several objects of the invention may be noted the provision of apparatus of the class described wherein the last contact is as free from pitting, corrosion and smudging as any of the others therein; the provision of apparatus of this class in which mutual wiping of 15 all contacts is effective after they are all closed; and the provision of apparatus of the class described which is relatively simple in construction and operation. Other objects will be in part obvious and in part pointed out hereinafter.

20 The invention accordingly comprises the elements and combinations of elements, features of construction, and arrangements of parts which will be exemplified in the structures hereinafter described, and the scope of the application of 25 which will be indicated in the following claims.

In the accompanying drawing, in which are illustrated several of various possible embodiments of the invention,

Fig. 1 is a fragmentary side elevation showing 30 a single row of separated contacts;

Fig. 2 is a view similar to Fig. 1 but reduced in scale and showing the contacts forced together;

Fig. 3 is a diagrammatic assembly; and,

Fig. 4 is a view similar to Fig. 1 showing another form of the invention.

Similar reference characters indicate corresponding parts throughout the several views of the drawing.

As may be seen more in particular by referring 40 to my said application, certain apparatus which I have constructed requires an eddy current drum 1 (Fig. 3 herein), driven by driver 3 associated with an electro-magnetic armature 5, the latter being fastened to a driven member 7. The speed 45 of the driven member 7 determines the angularity of a lever 9 controlled from a spring loaded governor 11. The arm 9 controls a lever 13 which, in said application, caused successive 50 openings of contacts in a row of contacts accordingly as the speed increased, thereby throwing resistance into a circuit 15. The circuit 15 is a circuit by means of which a battery 17 is caused to energize the field windings 19 on the 55 electro-magnetic armature 5.

In the present invention it is desired to improve the operation of banks of contacts.

Such large resistance values are required in the electric governors for air conditioning that it is found necessary to thus put contacts in 5 multiple series rows and still operate them from a common lever, and the present invention applies both to single and multiple series rows. Getting both rows to positively close when using a fixed stop has developed into a serious service 10 problem. Certain contact leaves also did not get sufficient contact pressure when wiping action occurred. Hence they were not self-cleaning resulting in inefficient contacting with pitting, 15 corrosion and smudging.

Referring specifically to Fig. 3, it will be seen that one contact roller 25 is used but more may be used if more contact series are desired. One of these rollers 25 is shown in Figure 1 opposite a row of button contacts 27 which are located on 20 flexible leaf springs 29, the latter being mounted on an arbor 31 but insulated from one another. The leaf springs 29 are adapted to be bent as shown in Figure 2 when the pressure roller 25 advances to the left. In so bending they successively contact from right to left with the contact pressure between pairs increasing as the number of contacts increases, and vice versa. Thus as the roller 25 proceeds to the right under increased speeds, the contacts successively open 30 to the right and successively cut in resistance units.

Opposite the last leaf spring 29 and contact 27 is slidably mounted a preloading stop 33, said stop 33 acting resiliently against a spring 35, the latter abutting a cotter key 37. The cotter key 37 intersects an opening 39 in a fixed stop-screw 41. As shown in the drawing, said spring 35 is within said opening 39.

The stop-screw 41 is threaded for adjustment 40 through an arm 43 and adapted to be locked in any adjusted position by means of a lock nut 45. A seal 47 acts as a further lock and indicator of any tampering with the apparatus.

It will be seen from the above that as the pressure roller advances to the left, the successive leaf springs or blades are bent to the left, thereby successively contacting the button head contacts 27 and thereby shorting out whatever resistance may be placed across successive contacts.

The action is ideal because there is substantially right angular movement of the contact surfaces until contact is attained, after which a lateral wiping action maintains the contacts 55

bright and efficient. At the same time the increasing pressure between contact surfaces, as the leaf springs are bent, provides a very smooth cutting out of the resistances. It will be understood that the resistance at a given pair of contacts is reduced in a proportion to the pressure increase at the contacts.

As the last contact 27 is contacted by the second-to-last contact 27, it is in turn pushed to the left and forces the resiliently mounted resistance stop 33 to the left. This action permits wiping between the last two contacts in the same manner that the other contacts wipe and permits of further wiping of all contacts after all are closed. However, it is not proper to permit this action to proceed indefinitely and it does not do so, for the last contact finally strikes the fixed surface 49 on the adjustable fixed stop 41.

The movement of the plunger or plug 33 is of the order of one-sixteenth of an inch which affords proper wiping action. This portion of the invention may be characterized as the provision of a series of spring mounted contacts, the last one of which engages a pre-loaded plunger stop having a definitely limited movement to prevent excess deflection of the spring mountings for said contacts. By this means is obtained the controlled pressure wiping action. This also provides a preloaded range of movement for the roller 25 toward the right under increasing speed conditions. During this range of movement no resistance is cut in as no contacts open and the apparatus may gain a certain minimum speed without hunting over the range.

It will be seen from the above that the pre-loaded plunger 33 effects an equalizing feature, so that if adjustment of the pressure roller 25 is inaccurate, the plunger 33 will permit proper complete engagement.

Thus, by means of this invention, not only is the action of a single row of contacts improved, but provision is made for increasing the capacity of this type of resistance by permitting two banks of the same to be successfully operated simultaneously, if desired.

It will be understood that in Fig. 3, the showing of one row of three contacts and two resistances is suggestive only, and that as many contact banks may be used as may be desirable in a given design.

As shown in Figure 4, the invention may be carried out by providing a series of leaf springs 29 of which the last 30, is made stronger than the remainder. The sliding plug 33 is omitted but the fixed stop 41 being retained at a predetermined distance from the last, relatively strong spring 30. By this means, bending of the last contact is effected for predetermined distance and thus wiping is effected, but the desired predetermined final stop is had. In either the Fig. 1 or the Fig. 4 form, the action at the last contact has the effect of preloading the contacts in the respective row so that there is a delay in cutting in resistance as speed increases over a given pe-

riod of time, that is, all contact opening is delayed until the last, preloading contact traverses its path of movement from the fixed stop surface 49. The provision of this movement also permits full wiping contact at all contact points and the successful operation of a plurality of contact banks from a single source of movement. The movement being adjustable permits adjustment of the degree of preloading so that the apparatus may readily be set to operate at best efficiency under any of varying outside conditions.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In electrical shunting apparatus having a series of movably mounted shunting contacts and pressure means operable from one end against the series to successively close and open the same, means supporting the last contact at the other end of the series effecting a higher resistance to movement than is effected in connection with the other contacts, and an adjustable fixed stop for adjustably determining the maximum movement of said last contact.

2. In electrical shunting apparatus having a series of movably mounted shunting contacts and pressure means operable from one end to successively close and open the series, a separate movable stop engaging the contact at the other end of the series, resilient means normally holding said stop to resist opening of the series during movement after closure thereof, and an adjustable fixed stop for determining the amount of said movement when all contacts are closed.

3. In electrical shunting apparatus having a series of movable spring-mounted contacts and movable pressure means operable from one end of the series, an adjustable fixed stop at the other end of the series, a movable stop supported by said fixed stop and adapted to be engaged by the last contact of said series, and resilient means reacting between the fixed stop and the movable stop.

4. In electrical shunting apparatus having a series of movable spring-mounted contacts and movable pressure means operable from one end of the series, a movable stop engaging the opposite end contact of the series, resilient means cooperating with said movable stop providing substantial pre-loading between all contacts after they have closed to maintain a complete closure for a predetermined part of the movement of the pressure means, a positive stop adapted to limit the motion of all contacts while closed and means for adjusting said positive stop so that the limited motion and amount of pre-loading may be predetermined.
